(57) **CLAIM**

We claim the ornamental design for a mobile phone key-chain cradle, as shown and described.

DESCRIPTION

FIG. 1 is a bottom perspective view of a mobile phone keychain cradle, showing my new design in a deployed configuration and holding a mobile phone;

FIG. 2 is a front elevational view thereof, illustrated without the mobile phone;

FIG. 3 is a rear elevational view of FIG. 2;

FIG. 4 is a right-side elevational view of FIG. 2, the left-side elevational view being a mirror image thereof;

FIG. 5 is a top plan view of FIG. 2;

FIG. 6 is a bottom plan view of FIG. 2;

FIG. 7 is a perspective view thereof, illustrated in a flat configuration with a rivit of the design omitted for clarity of illustration; and,

FIG. 8 is a top plan view of FIG. 7, the bottom plan view being a mirror image thereof.

The broken lines showing a mobile phone and keychain ring in FIG. 1 depict environmental matter and form no part of the claimed design.
